CLAIM

The ornamental design for a slide bucket lid mouse trap, as shown and described.

DESCRIPTION

FIG. 1 depicts an unassembled downward view of the slide bucket lid mouse trap showing my new design;

FIG. 2 depicts an unassembled downward view of the slide bucket lid mouse trap;

FIG. 3 depicts a forward downward facing view of the slide bucket lid mouse trap;

FIG. 4 depicts an unassembled bottom view of the slide bucket lid mouse trap;

FIG. 5 depicts an unassembled angled bottom view of the slide bucket lid mouse trap;

FIG. 6 depicts an unassembled downward view of the slide bucket lid mouse trap;

FIG. 7 depicts an assembled angled downward view of the slide bucket lid mouse trap;

FIG. 8 depicts a side view of the slide bucket lid mouse trap showing my new design, wherein the slide is seated inside of the bucket lid and the ramp slid into the female counter part located on the bucket;

FIG. 9 depicts an angled bottom view of the slide bucket lid mouse trap, wherein the slide is seated inside of the bucket lid and the ramp slid into the female counter part located on the bucket lid;

FIG. 10 depicts a downward view of the slide bucket lid mouse trap wherein the ramp is slid into the female counter part located on the bucket lid;

FIG. 11 depicts an angled downward view of the traps pivot point of the slide bucket lid mouse trap;

FIG. 12 depicts a side view of the traps pivot point of the slide bucket lid mouse trap;

FIG. 13 depicts a side view of the traps pivot point of the slide bucket lid mouse trap;

FIG. 14 depicts an angled bottom view of the traps pivot point of the slide bucket lid mouse trap;

FIG. 15 depicts a bottom view of the traps pivot point of the slide bucket lid mouse trap; and,

FIG. 16 depicts an angled bottom view of the traps pivot point of the slide bucket lid mouse trap.
